DREDGE

Filed Oct. 24, 1922

UNITED STATES PATENT OFFICE.

BERT O. GODFREY, OF SEATTLE, WASHINGTON.

DEEDGE.

Application filed October 24, 1922. Serial No. 598,547.

To all whom it may concern:

Be it known that I, BERT O. GODFREY, a citizen of the United States of America, and resident of the city of Seattle, in the county of King and State of Washington, have invented certain new and useful Improvements in Dredges, of which the following is a specification.

My invention relates to an improvement in dredges of the type which will bore into the material, such as mud, sand, gravel and the like, upon the bottom of a body of water, and which will lift this, together with any mineral deposits associated therewith, to a suitable point where it can be acted upon by a concentrator or other proper apparatus.

My invention is particularly intended for use in dredging for gold along river banks or along the shore of the sea where gold deposits occur.

The principal object of my invention is to provide a simple and compact arrangement whereby a force pump connected to two conduits may be operated at will, either as a borer or as a means for raising the gangue.

A further object is the construction of a very simple device of this character, and one which is cheap to construct.

A further object is the provision of means in such a dredge whereby the current which forms the suction lift may be reversed to accomplish the boring or digging.

My invention comprises those novel parts and combinations thereof which are shown in the accompanying drawings, described in the specification, and particularly defined by the claims terminating the same.

In the accompanying drawings I have shown my invention in forms which are now preferred by me.

Figure 1 is a sectional illustration of a simple form of my device.

Figure 2 is a similar section of a slightly modified form.

Figure 3 is a section on line 3—3 of Figure 1.

The illustrated embodiments of my invention consist simply of a suitable pump 1, acting as a force pump and taking water through the intake pipe 10 from the body of water on which a barge 5 floats, and delivering it through one of two conduits 4 and 7. One of these conduits, as the con-

duit 4, serves as a lift pipe through which the gangue and water is raised to a discharge outlet 41. The other conduit 7 terminates at its lower end adjacent the lower end of the conduit 4 to form a suction jet 6 by means of which a suction upwardly in the conduit 4 is created, as is well understood, and through which the gangue enters the conduit 4. Suitable valves or other means are provided for regulating the flow in the conduits and the direction thereof. To this end I have shown two valves 2 and 3.

The valve 2, in the form shown in Figure 1, serves merely to regulate the amount of water permitted to pass through the conduit 71, forming an extension of the conduit 7, to connect it with the pump 1. The valve 3 in this form serves either to open a passageway through the conduit 4 to the discharge end 41, or to close off this passageway. In the form shown in Figure 2 the valve 2' connects the pump 1 either with the extension conduit 71 or to a by-pass 31 connecting the pump with the upper end of the conduit 4. In this form the valve 3' serves either to open the passageway through the conduit 4 to the discharge end 41, or affords communication between the by-pass 31 and the lower portion of the conduit 4.

I have shown the conduits 4 and 7 as nested, the conduit 4 within the conduit 7, and I have shown a chamber 70 at the upper end of the conduit 7. These are mere matters of design, and although the design is my preferred one on account of its compactness and simplicity, yet it is within the scope of my invention to depart therefrom, and yet to remain within the scope of the appended claims. I have also shown the device as supported by means of a ball and socket joint, the ball 8 surrounding the conduit 7 and the conduit being slidable therein, and the ball being received in a socket 100 85 carried by the barge 5. This, while a convenient arrangement, is a matter of design only, and if desired the dredge may be otherwise supported.

The jet 6 may be of any suitable construction. I have shown a head 61 which is attached to the lower end of the conduit 7 and which curves inwardly and then upwardly to a point within the periphery of the lower end of the conduit 4, leaving a 110

space 62 between the end of the head 6 and the end of the conduit 4. Lugs 63 formed upon the head 61 engage the outside of the conduit 4 and space the head from the conduit 4 to properly position the head. This, it will be noted, leaves a central opening through the head 61 through which the gangue is drawn in.

Referring now to the form shown in Figure 1 and assuming that the pump 1 is in operation and that the valve 3 is turned in such manner as to leave the passageway through the conduit 4 open to its discharge end 41, and that the valve 2 is open, water 10 will be supplied through the intake pipe 10, the pump 1, the passage 71, the conduit 7 and thence upward past the suction jet 6, through the conduit 4 and out at the discharge end 41. This creates a suction 15 through the jet 6 as is well understood, and any loose material will be drawn upward therethrough and will be delivered as gangue at the discharge end 41.

Assuming, however, that it is desired to 20 bore or dig with the device, or to loosen more material from the bottom, the valve 3 is then turned to obstruct the conduit 4 and to close it off from its discharge end 41. Water now passes as before through the pump 1 and the conduit 7, but as the conduit 4 has been filled with water, it is repelled therefrom, and after passing the head 61 it is expelled through the suction jet in the reverse direction to that in which the 25 gangue is drawn up. This force, acting on the bottom, will stir up and loosen the material and thereafter the same may be withdrawn in the manner first described.

Referring to the form shown in Figure 30 2, and assuming that parts are in the positions shown in full lines and that the pump 1 is operating, water will pass as shown by the full line arrows, through the intake pipe 10, the pump 1, the passage 71, the conduit 7, past the head 61 and suction jet 6 and thence upward through the conduit 4 to its discharge end 41. Gangue is drawn up 35 through the suction jet 6 as before. To operate the device for digging or boring, however, the positions of the valves 2' and 3' are reversed to the positions shown in dotted lines. The flow now takes place in the direction of the dotted arrows, through the intake pipe 10, the pump 1, the by-pass 31, downward through the conduit 4 and thence out through the suction jet 6, the conduit 7 being filled with water. This causes the jet emerging at 6 to stir up and loosen the material on the bottom as in the former case.

It will be noted in both instances that the 40 action of the device as a digger or borer is dependent upon the filling of one conduit and consequent repulsion of any further water, causing the ejection of the surplus water through the jet 6. Its action as a

70 pump or dredge is caused by a movement of water past the jet 6 and out otherwise than through the jet 6, that is, out the conduit 4, causing a suction through the jet and a consequent lifting of loose material.

It will be understood that, inasmuch as the force pump 1 serves merely as a convenient source of water under pressure, it may be omitted when desired, and the intake pipe 10 will then be connected to some other suitable source of water under pressure, as, for instance, an elevated reservoir, this being the full equivalent of my pump.

What I claim as my invention is:

1. In combination, a force pump and two 80 conduits open at their lower ends, one of said conduits being connected to the pump, and terminating at its lower end in an annular suction jet directed upwardly within the lower end of the second conduit, and means whereby water from said pump may be directed upwardly through said jet and the second conduit, or downwardly through the lower end of the first conduit, at will.

2. In combination, a force pump and two 85 conduits, one of said conduits being connected to the pump, and terminating within the lower end of the second conduit to form an annular, upwardly-directed suction jet, and a valve movable to close said second 90 conduit to expel water through the opening in said suction jet.

3. In combination, a force pump and two 95 conduits open at their lower ends, one of said conduits being connected to the pump, and terminating at its lower end in an annular suction jet directed upwardly within the lower end of the second conduit, a valve 100 for controlling the flow through said first conduit, and a second valve for directing 105 the flow of water upwardly through the second conduit or downwardly through the open end of the first conduits, at will.

4. In combination, a force pump and two 110 conduits open at their lower ends, one of said conduits being connected to the pump, and terminating at its lower end in an annular suction jet directed upwardly within the lower end of the second conduit, a bypass connecting said second conduit with the pump, and valves movable to direct the current upwardly through the second conduit to its upper end, or downwardly therethrough and through the open end of the jet.

5. In combination, a force pump and two 115 conduits open at their lower ends, one of said conduits being connected to the pump, and terminating at its lower end in an annular suction jet directed upwardly within the lower end of the second conduit, a by-pass connecting said second conduit with the pump, a valve at the junction of said by-pass and second conduit movable to close off selectively either the upper discharge 120 end of said second conduit or the by-pass, 125

and a second valve movable selectively to connect said pump either with the by-pass or with the first conduit.

6. In combination, a force pump and two nested conduits, open at their lower ends, the outer conduit being directly connected to the pump, and being turned inwardly and upwardly at its lower end to form a suction jet directed upwardly within the lower end of the inner conduit, said inner conduit leading upward to a discharge outlet, a by-pass connecting said inner conduit with the pump, a valve adapted to close either said by-pass or said inner conduit, and a second valve movable to direct water either through said by-pass or through said outer conduit.

7. In combination with a suction jet, a force pump and a pair of conduits connect-

ing said pump and the suction jet, one of 20 said conduits normally serving to supply water to operate said suction jet, and the other conduit normally serving to lift material raised by said suction jet to its discharge end, and means for directing water 25 from said first conduit outwardly through said suction jet.

8. In combination with a source of water under pressure, two conduits, one thereof being connected to the pressure source, and 30 terminating within the lower end of the second conduit to form an upwardly directed suction jet, and means operable to close said second conduit to expel water through said jet. 35

Signed at Seattle, King County, Washington this 14th day of October, 1922.

BERT O. GODFREY.
